(74) Attorney, Agent, or Firm — Banner & Witcoff, Ltd.

(52) U.S. Cl.

CLAIM

USPC **D21/686**

The ornamental design for an implement for exercise rack,
as shown and described.

(58) **Field of Classification Search**

DESCRIPTION

USPC 312/351.1, 351.3, 351.5; 482/38, 92, 94,
482/98, 99, 101, 104, 120, 133;
D21/662, 673, 686, 691, 694, 798, 826;
D25/62, 66, 68, 119, 126, 136; D6/329;
D8/323, 354; 411/366.1
CPC A63B 21/00047; A63B 26/00; A63B 5/00;
A63B 2225/093

See application file for complete search history.

(56) **References Cited**

FIG. 1 is a top, front, left perspective view of an implement
for exercise rack showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top, front, left perspective view shown in a
condition of use thereof.

The broken lines in the drawings are for the purpose of
illustrating environmental structure, which forms no part of
the claim design.
